UNITED STATES PATENT OFFICE.

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,180,631.

Specification of Letters Patent. Patented Apr. 25, 1916.

Application filed May 25, 1914. Serial No. 840,748.

To all whom it may concern:

Be it known that I, NELSON M. BAKER, a citizen of the United States, residing at Southbridge, in the county of Worcester 5 and State of Massachusetts, have invented certain new and useful Improvements in Ophthalmic Mountings, of which the following is a specification.

My invention relates to improvements in 10 ophthalmic mountings, and has particular reference to that type of mounting in which a wide bridge is employed, such as in shell or imitation shell goods, or in the reading type of gold or gold filled ware.

15 The leading object of my invention is the provision of an extremely comfortable and satisfactory mounting which can make use of the large round eye at present popular without necessitating decentering of the 20 lenses and yet will permit of attainment of the correct pupillary distance between the centers thereof.

25 A further object of my invention is the provision of a mounting of this character in which the mounting for the lenses may act as a positioning member for engaging the nose, and in which the gripping members will be properly supported to correctly hold the mounting in position on the face.

30 Another object of my invention is the provision of a mounting which shall be neat and attractive in appearance and have a minimum number of projecting parts liable to catch on the clothing, interfere with the 35 symmetry of the mounting, or collect dirt, also to provide a simple but efficient and durable mounting constructed from shell or other relatively soft material.

Other objects and advantages of my improvement should be readily apparent by 40 reference to the following description taken in connection with the accompanying drawings, and it will be understood that I may make any modifications in the specific details of construction shown and described 45 within the scope of the appended claim without departing from or exceeding the spirit of my invention.

Figure I represents a front elevation 50 illustrating one form of my invention. Fig. II represents a top plan view thereof showing the guards in open position.

In the drawings, in which similar characters of reference are employed to denote

corresponding parts throughout the several 55 views, the numeral 1 designates the rim or frame pieces in which are mounted the lenses 2, while connecting the said rim is the bridge member 3. It is to be noted that I have illustrated this bridge member as 60 formed of relatively wide material, and as having its arch forming substantially a continuation of the curve of the inner portion of the frames 1, this shape preferably being such that both the inner arch of the 65 bridge and also the adjacent portions of the frames 1 will rest against the nose, the frames 1 thus serving to a certain degree as positioning members for the mounting and insuring the same being correctly placed on 70 the face of the wearer and preventing any lateral displacement thereof. It is to be particularly noted in connection with this construction that there is an absolutely smooth or flush joint between the frames 75 and the bridge member. Consequently there are no corners, bumps or the like to bear against and irritate the nose of the wearer. Consequently I have provided an extremely comfortable and desirable mounting. 80

In that form of my invention illustrated in Fig. I, I have shown as formed at each end of the bridge member the recess 4, formed by cutting away the portion of the frame 1, while mounted in said recess and extending 85 forwardly and rearwardly therefrom is the guard arm 5 bearing at one end the guard 6 and at the other end being preferably provided with a handle portion 7 for manipulation thereof. Passing vertically through 90 the recess and engaged thereabove and therebelow in the wall of the recess is a pivot member preferably having a plain portion 8 terminating in a shoulder 9 and having a lower threaded portion 10 engaged in the 95 frame 1. The guard arm or lever 5 is mounted upon the plain portion of said pivot, while mounted on the pivot and contained within the recess is a spring 11 for actuating the lever. 100

It is to be understood in connection with the form shown in Fig. I, that the pivot may if desired be provided with a head 14 engaging the upper portion of the mounting so that tightening of the pivot into place will 105 serve to slightly decrease the size of the rim 1 and aid in securing the lens in position, the open joint provided in this form

of my construction permitting of slight expanding of the rim when placing the lens in position therein.

As previously mentioned, in my invention, the usual bumps, shoulders, or pivot seats, common in this type of eyeglass are entirely eliminated. This produces a double advantage in that it will permit of the attainment of a narrower pupillary distance and consequently the use of larger lenses without the necessity for decentering of the same, and also prevents any possibility of irritation of the nose on account of said bumps or the like touching thereagainst when the mounting is in position. At the same time if desired the mounting may be so fitted that the portions 1 will serve as guards or positioning members and aid in setting the mounting in position on the face of the wearer, while the upper and lower bearing portions of the guard serve almost entirely as gripping members to engage the nose at two points to prevent any tilting or swinging movement of the mounting thereon and anchor the same in position. This supporting of a portion of the weight by the bridge and frame thus permits of less spring tension on the arm and consequently the various parts coöperate to produce an extremely comfortable mounting. It is further to be noted that by the use of my invention it is possible to employ an extremely wide bridge, such as is particularly desirable with shell or other reading glasses, and at the same time to have the guards fit in correct position upon the nose while being of regular size. The advantage of this should be readily apparent by reference to Fig. I, for example, in which it will be seen that the guards 6 are located at about the

middle of the mounting, while it will be further noted that with a wide bridge such as here employed, should the guards be placed on top of the bridge, as is the usual position of mounting the same, the tops of the guards would come as high if not higher than the upper edge of the lenses, and consequently would not hold the mounting in correct position on the face of the wearer. With my improved method of mounting the guards, however, as before mentioned, they come sufficiently low to correctly fit the nose and thus both satisfactorily retain the mounting while combining with the other features thereof to provide a most comfortable and satisfactory eyeglass.

I claim—

A one-piece mounting comprising a central bridging member having a lens engaging rim integral with each end thereof, said bridge being of heavy but resilient material and having a slot or recess formed through the rim and adjacent portion of the bridge at each end thereof, a pivot post extending downwardly through the bridge and transversely of the recess at each end of the bridge, a guard lever and an actuating spring therefor, mounted on each of the pivots within the recess, whereby tightening of the pivot serves both to secure the lever and spring in position and also to spring together the split ends of the rim to tightly secure a lens in position within the rim, substantially as described.

In testimony whereof I affix my signature in presence of two witnesses.

NELSON M. BAKER.
